LAND, A CORPORATION OF MARYLAND.

TRAIN-CONTROLLING MECHANISM.

1,010,372.

Specification of Letters Patent. Patented Nov. 28, 1911.

Original application filed May 23, 1910, Serial No. 562,986. Divided and this application filed October 7, 1910. Serial No. 585,742.

To all whom it may concern:

Be it known that we, RICHARD T. JONES and FRANK T. JONES, citizens of the United States, residing at Baltimore, in the State of Maryland, have invented certain new and useful Improvements in Train-Controlling Mechanism, of which the following is a specification.

This invention relates to an improved controlling mechanism for railway trains and has particular reference to a device of this character which shall be automatic in its operation and actuated through the instrumentality of an arrangement of electrical circuits.

One object of the invention is to provide an improved signal-operated mechanism on the vehicle whereby to give audible and visual warning signals to the engineer as the vehicle approaches a block which is already occupied by a train.

Another object is to combine the signal mechanism with a mechanism for automatically applying the air-brakes if the engineer disregards the warning signal and attempts to take his train into an occupied block.

A further object is to provide means for resetting the warning signal mechanism upon the automatic operation of the brake controlling device, whether the brakes are thereby applied or not, it being possible that between the time the warning signal is given and the moment when the air-brakes would be applied, the block may become clear and in such instance the brakes would not be applied.

With these and other objects in view the invention is illustrated in the accompanying drawing in which,—

40 Figure 1 is a diagrammatic view of a portion of a trackway and also of the devices and circuits on the vehicle for controlling signals thereon and for actuating the air-brakes,—the signal devices being shown in the operated position. Fig. 2, is a diagrammatic view of the trackway showing a plurality of blocks thereon and the rail sections and circuits employed to control the signal and brake actuating devices on the vehicle. 50 Fig. 3 is a view similar to that shown in Fig. 1, with the exception that the position of the vehicle is such as to put the air-brake controlling devices in the operated position.

Fig. 4, is a sectional detail of the air-valve trip device and the connections between the same and the speed-indicator casing. Fig. 5, shows a sectional elevation of the indicator casing and also shows the hinged door and devices actuated by the movement of the door for setting the air-valve trip, and Fig. 6, is a sectional detail through the cover of the indicator housing and shows the locking flange and swinging arm to engage the same.

The present invention is fully shown and described in our pending application for patent filed May 23rd, 1910, Serial Number 562,986 of which the present application is a division.

Referring to the drawings by numerals, 1, designates one of the rails and, 2, the other rail on which the vehicle travels and which are arranged in blocks, 3, and, 4, by means of suitable insulations, 5. Short rail sections, 6, and, 7, respectively are provided at the side of the rails and at spaced-apart intervals,—the latter being substantially at the exit end of the block and the former nearer the entrance end thereto. These rail sections are preferably arranged parallel with the rails and to the outer side thereof and in the present instance the section, 6, has position farther from the rail, 1, than the section, 7, it being desirable that said sections be out of line with each other, so that one contact on the vehicle may engage one series of sections, 6, while another contact, also on the vehicle may engage the other series of sections, 7. In the present instance each block is provided with a source of electrical energy at its exit end, such as batteries denoted by the numerals, 8, and the poles of which are connected to the two rails.

Each rail section, 6, is in electrical connection by means of a wire, 9, with a contact plate, 10, and an armature, 11, is pivoted so that its free end may be moved into contact with said plate, 10, through the action of an electro-magnet, 12, when the latter is energized. A wire, 13, extends from rail, 1, to one side of a battery, 14, while a wire, 15, extends from the other side of the said battery, 14, to the armature, 11.

The rail-sections, 6, are utilized to effect an operation of the caution or warning signals on the vehicle and as such warning or

caution signal is given because of the occupancy of the block ahead by another vehicle or train, the devices operating in connection with said sections, 6, must be in electrical communication with something in the block ahead which will indicate the presence of a train therein.

By reference to Fig. 2, it will be seen that a wire, 16, extends from the entrance end 10 of rail, 1, of block, 4, back to and connects with the warning magnet, 12, in block, 3, and that a wire, 17, extends forwardly from the outer side of said magnet, 12, to and connects the entrance end of rail, 2, in said 15 block, 4. It will thus be seen that if block, 4, were clear, a circuit would be completed from one side of battery, 8, by rail, 1, wire, 16, to magnet, 12, thus energizing the latter and attracting the armature, 11; then by 20 wire, 17, to rail, 2, of said block, 4, and back to battery, but as there is a vehicle, 18, in block, 4, the circuit from battery, 8, of that block is from battery to rail, 1, through axles of vehicles to rail, 2, and back to battery, 25 thus wires, 16, and, 17, are short-circuited and magnet, 12, is deenergized at such times and armature, 11, will drop away from contact, 10, so that rail section, 6, will be entirely cut-off from battery, 14.

30 At the exit end, each block is provided with a rail-section, 7, to control the air valve on the vehicle to apply the brakes in case the block immediately ahead is occupied by a vehicle or train. Each rail section, 7, is 35 connected by a wire, 19, to a contact plate, 20, with which an armature, 21, makes contact when attracted by magnet, 22. A battery, 23, is connected to the armature by wire, 24, and a wire, 25, connects the other 40 side of the battery, 23, with rail, 1. By reference to Fig. 2, it will be seen that magnet, 22, is included in the circuit that also energizes magnet, 12, and consequently both of 45 said magnets are deenergized at the same time when a train enters block, 4, and will be energized when said block, 4, is clear. The reason for this is that both rail sections, 6, and, 7, have to do with the conditions in the block ahead and are thrown into circuit 50 with batteries, 14, and, 23, respectively in case the block ahead is clear so as to prevent the operation of the warning signals and the application of the air-brakes on the vehicle when the contacts on the vehicle brush over said rails, as will presently be described, by picking up, as it were, a current from the batteries, 14, and, 23, to maintain the circuits on the vehicle.

55 By reference to the diagrammatic Figs. 1 and 3, it will be understood that the numeral, 26, designates the wheels of the vehicle and, 27, the axle thereof. An air-signal pipe, 28, is provided on the vehicle at any convenient location and has a valve, 29, 60 and a signal arm, 30, that is carried on the

said valve. This arm, 30, also serves as an armature for an electro-magnet, 31, which, as long as it is kept energized, will keep the arm or armature in the safety position against the core of the magnet. An air whistle, 32, is also connected to the casing of the valve, 29, so that when the armature is dropped to the danger position the whistle will sound and thus give an audible signal to the engineer as well as a visual signal. 70 These two signals are maintained in the safety condition by a circuit normally on the vehicle that maintains the magnet, 31, in an energized condition. This circuit includes battery, 33; wire, 34; plate, 35; contact shoe, 36; wire, 37; magnet, 31, then by wire, 38, to axle, 27, wires, 39, and, 40, to contact plate, 41, and then to plate, 42, and wire, 43, back to battery, 33. It will thus be seen that when shoe 36, and plate, 41, 80 are in the normal pendant position, as in Fig. 3, they are in contact with plates, 35, and, 42, consequently the signal circuit will be maintained and magnet, 31, will be kept energized. 85

The vehicle travels over the rails, 1, and, 2, and the contact shoe, 36, is located on the vehicle so it may depend therefrom and successively wipe over the rail sections, 6, in the various blocks. During the travel of the vehicle between the rail sections, 6, the normal signal circuit will be maintained from battery, 33, but when the shoe, 36, wipes over a rail section, 6, the normal signal circuit will be interrupted and another circuit must be 90 substituted or the magnet, 31, will become deenergized and allow arm, 30, to drop thus giving the danger signal. It has heretofore been explained that if the block ahead is clear, track magnet, 12, will be energized 95 and armature, 11, will throw rail section, 6, in a circuit with battery, 14, therefore if the block ahead is clear when the shoe, 36, reaches rail section, 6, the normal signal circuit on the vehicle from battery, 33, may 100 be interrupted but simultaneously therewith or prior thereto, a circuit from battery, 14, will be substituted and will be from said battery by wire, 15, to armature, 11; contact, 10, wire, 9, to rail section, 6; then by shoe, 36, on vehicle; wire, 37, to magnet, 31, to keep the latter energized; then return by wire, 38, to axle, 27, wheel, 26, to rail, 1, and from said rail by wire, 13, back to a battery, 14, so as to hold the signals on the vehicle 110 in the safety position until shoe, 36, passes off rail section, 6, and resumes its normal position against contact 35, so as to restore the normal signal circuit on the vehicle. On the other hand if the block ahead is occupied by a vehicle the magnet, 12, will be deenergized and armature, 11, will drop away from contact, 10, thus cutting out rail sections, 6, from battery, 14, therefore when the contact shoe, 36, on the vehicle passes over said 115 120 125 130 135

rail section, 6, there will be no substitute circuit to take the place of the normal signal circuit and magnet, 31, on the vehicle will become deenergized and let armature, 5, 30, drop and whistle, 32, will sound.

In addition to the warning signals just described the invention makes use of an air-brake applying mechanism that operates to apply the brakes if the engineer fails to 10 stop his train, or proceeds toward the block already occupied above a low rate of speed as will now be explained.

An air pipe, 44, is provided at a convenient point on the vehicle which communicates with the air-brake mechanism and a valve casing, 45, is provided in said pipe so that the stem, 46, of a valve in said casing may project on the exterior and carry a lever, 47. An arm, 48, is also provided on 20 the valve stem and carries a weight, 49, which constantly tends to move the valve to the position that would cause an operation of the brakes. The lever, 47, of the valve has an offset or right-angle projection, 50, 25 which is engaged by a lug, 51, on the pivot-end of an armature or trip, 52,—the free end of which latter is held normally by an electro-magnet, 53. This magnet, 53, is kept energized normally by a circuit on the 30 vehicle which shall be termed the brake circuit hereinafter to be described.

The casing, 45, has a tubular extension, 54, at one side, see particularly Fig. 4, which connects with and opens into an indicator housing, 55. This housing is to contain a speed-indicating device of suitable construction such as referred to in our pending application Serial No. 502,698 filed June 17th, 1909, to effect an operation of the brakes on 35 a train that approaches or enters a block already occupied by a train at a rate of speed greater than a predetermined speed that is considered safe. To this end the said indicating device has a central revoluble shaft, 56, which carries a contact arm, 57, that is swung in one direction as the speed of the vehicle is increased and is moved in a reverse direction as the speed of said vehicle is decreased.

50 By reference to Figs. 3 to 6 of the drawings it will be seen that this housing has two segmental contact plates, 58, and, 59, respectively over which the contact arm, 57, may swing. These plates are insulated 55 from each other and are included in different circuits as will presently appear. The purpose of this housing and the immediate devices associated therewith is to require the engineer to bring his train to a full stop before brakes, after an automatic application, can be released, as set forth and claimed in our said divisional application Serial Number 562,986, and while these devices will be explained herein they are made the subject of claims in said pending application.

The housing, 55, of the indicating device is provided with a cover or lid, 60, which is hinged at, 61, to the housing so that it may be swung open when desired. A glass plate, 62, is provided in the cover so that the location of the contact arm may be viewed while the cover is closed. This cover is provided with a lever or arm, 63, that extends downwardly into the housing and has position adjacent the end of the tubular extension, 54, as clearly seen in Fig. 5, where it may contact with the up-turned end, 64, of a rod, 65, that extends through and is movable longitudinally in the said tubular extension, 54. This rod 65, engages a bolt, 66, 70 at one end which projects into the valve casing, 45, and a spring, 67, encircles the bolt and keeps the latter yieldingly pressed toward the valve casing.

On the interior of the valve casing the 85 stem, 46, carries a head, 68, which latter is provided with a circumferential shoulder, 69, with which the bolt, 66, on rod, 65, engages, when the valve has been released and is in the operated position, and said bolt 90 prevents the return rotation of the head, 68, to set the valve until the engineer complies with certain requirements,—one of which is that the train be brought to a stop. In order to carry out this idea we have provided the cover, 60, of the indicator housing with an annular flange, 70, which has a slot or opening, 71, at one point only (see Fig. 6) and on the end of the indicator shaft, 56, we mount an arm, 72, which like arm, 57, turns only with the said shaft. This arm, 72, extends toward and has its outer free end projecting over the annular flange, 70, on the cover, so that when the vehicle is in motion said arm, 72, will project over the 105 said flange and while so projected the cover can not be opened. When, however, the vehicle is brought to a stop the arm, 72, will project over the slot or opening, 71, as in Fig. 6, and the cover may then be swung 110 open. During the opening of the cover the arm, 63, thereon will swing inwardly and against the up-turned end, 64, of rod, 65, thus drawing said rod toward the indicator and withdrawing the bolt, 66, from 115 beneath the shoulder, 69, on head, 68, so the latter may be returned with arms, 47, and, 48, to their normal locked position as in Fig. 1. In order to hold the arms, 47, and, 48, in the normal inoperated position 120 the electro-magnet, 53, must be maintained in an energized condition.

By reference to Figs. 1 and 3 it will be seen diagrammatically, that a battery, 73, is carried on the vehicle and that a contact plate, 74, is connected by a wire, 75, with one side of said battery. A yielding contact shoe, 76, is also carried on the vehicle and depends therefrom so as to have position in a vertical plane where it may wipe 130

over the series of short rail sections, 7, as the vehicle passes the latter in succession. A wire, 77, connects the shoe, 76, with the contact plate, 59, of the speed indicator with which the indicator arm, 57, in the present instance is shown in contact, thus indicating that the vehicle is traveling at a rate of speed above the predetermined speed at which it is deemed unsafe to permit it to enter an occupied block.

The indicator arm, 57, is connected by wires, 78, and, 79, to one side of the electromagnet, 53, so that the electrical energy from battery, 73, may be conveyed by wire, 75, plate, 74, shoe, 76, wire, 77, arm, 57, and wires, 78, and, 79, to the magnet, 53. The other side of the magnet, 53, has a wire, 80, that connects with wire, 88; axle, 27; wires, 39, and, 81, to a yielding plate, 82, contact plate, 83, and wire, 84, back to the other side of battery, 73. It will thus be seen that battery, 73, keeps magnet, 53, energized so long as shoe, 76, and yielding plate, 82, are in contact with plates, 74, and, 83, and the arm, 57, is on what might be termed the high-speed contact plate, 59. In case the indicator arm, 57, is in contact with low-speed plate, 58, indicating that the vehicle is traveling at a reduced speed and that it may enter a block already occupied, a different circuit will be formed to maintain the magnet, 53, in an energized condition, which circuit for convenience in identification, may be termed a low-speed circuit, and 35 includes battery, 85, wire, 86; low-speed contact plate, 58, arm, 57, that would under the stated circumstances be on plate, 58; wires, 78, and, 79, to magnet, 53, and wire, 87, back to battery. It will thus be seen 40 that when the vehicle is traveling at a reduced or low-speed and arm, 57, is on low-speed contact, 58, the magnet, 53, will be kept energized no matter whether shoe, 76, and plate, 82, are in circuit with battery, 73, 45 or not.

Suppose now the vehicle approaches an occupied block with the valve devices and speed indicator arm in the position shown in Fig. 1,—the shoe, 76, will wipe over rail section, 7, and be bowed or bent backwardly out of contact with plate, 74, and the circuit through magnet, 53, will be broken and the latter deenergized, consequently arm, 47, will drop and valve stem, 46, will be turned 55 to effect an operation of the air brakes. The brakes must remain set until the valve stem is returned and this cannot be done until the vehicle comes to a stop and the arm, 72, registers with slot, 71, in the cover flange, 60, because the cover cannot be opened to retract the bolt, 66, from engagement with the head, 68, on the valve stem. It will thus be seen that the engineer cannot release his brakes until his train is brought to a stop and consequently cannot proceed regardless of the

signals given him. If on the other hand the block ahead is clear, the magnet, 53, will not be deenergized when the shoe, 76, is bent out of contact with plate, 74, by wiping over rail section, 7, because another circuit this time from rail-section battery, 23, will be substituted to keep magnet, 53, energized. In this latter case the circuit will be as follows: from battery, 23, by wire, 24, armature, 21, contact, 20, and wire, 19, to rail-section, 7; then by shoe, 76, wire, 77, high-speed contact plate, 59, indicator arm, 57, wires, 78, and, 79, to magnet, 53; then from magnet, 53, by wires, 80, and 38, axle, 27, and wheel, 26, to rail, 1, and from said rail, 1, by wire, 25, back to other side of battery, 23, thus completing the circuit. It will therefore be seen that magnet, 53, is kept energized when the block ahead is clear by substituting a rail circuit, while the normal circuit is interrupted because of the bowing of the shoe, 76.

In case it is desired to employ two engines on a train some means must be provided to prevent the operation of the brakes on the second engine because of the presence of the first engine in the block and to effect this we provide wires, 88, and, 89, and a switch, 90, which when the switch is closed effects a shunt around the indicator 25 and causes a circuit to be formed and maintained from battery, 85, wire, 87, magnet, 53, wire, 79, wire, 88, switch, 90, and wire, 89, back to battery, 85, thus keeping the magnet, 53, energized.

In carrying out our invention we have found it expedient to provide simple means for resetting the air-brake levers, 47, 48, and, 52, which will now be described.

By referring to Figs. 1 and 3 it will be seen that an air storage reservoir, 91, is provided on the vehicle, and that a pipe, 92, extends from said reservoir to a point adjacent the tubular extension, 54, and is provided with a valve, 93, having a lever, 94. The tubular extension is provided with a slot, 95, and a member, 96, is carried on the rod, 65, that extends through the tube and said member engages the lever, 94, of the air-valve, 93, so that the movement of the rod may be utilized to actuate said valve. It will therefore be seen that if the rod, 65, is given a longitudinal movement as the cover, 60, of the speed-indicator is opened, such movement will be imparted to the lever, 94, and open the valve, 93, sufficiently to allow air from the reservoir, 91, to pass. Beyond the valve, 93, the pipe, 92, terminates at a point in close proximity to the valve casing, 45, and said pipe carries a small plunger, 97, which is driven outwardly by the air that is admitted behind it when the cover, 60, is opened and the rod, 65, is moved thereby. This plunger, 97, forms a stop for arm, 47, so that said arm 130

will rest thereon when it is in the lowered or operated position. If therefore, after the train has been stopped by the operation of the air brake valve referred to herein, 5 and it is desired to reset the valve; the engineer may open the cover of his indicator which causes air to pass from reservoirs, 91, to plunger, 97, and by driving said plunger outwardly will throw the levers, 47, 48, and 0 trip, 52, back into place and the magnet, 53, will at once attract the trip, 52, and hold the devices in the reset condition. The signal arm, 30, is reset in a very similar manner in that an air pipe, 98, from the reservoir, 91, has a valve, 99, which is automatically actuated each time the shoe, 76, rides over a rail section, 7, and permits air to pass through pipe, 100, to a plunger, 101, on which the operated signal arm rests. In the 0 case of the signal, however, it will be seen that each time the shoe, 76, is bent a blast of air will be admitted from reservoir, 91, through pipes, 98, and, 100, to plunger and the signal arm, if down, will be thrown up 5 and held by the electro-magnet, 31, until released by the signal shoe, 36, breaking the circuit.

It will thus be seen that the signals are actuated by the movement of the shoe, 36, 0 and are reset by the movement of contact shoe, 76, of the air-brake device.

A wire, 102, extends from contact plate, 59, to a contact, 103, so that in case the speed indicator should become disarranged the 5 arm, 57, may be retained in contact, 103, and the current from contact plate, 59, will pass by wire, 102, to arm, 57, to wire, 78.

Having thus described our invention what we claim and desire to secure by Letters 0 Patent is,—

1. In a train controlling mechanism the combination with a wheeled vehicle having an electro-magnet, of a signal device on the vehicle; a contact shoe; a circuit normally including the electro-magnet and contact shoe to hold the signal in one position until released by the contact shoe; a second contact shoe, and means actuated by said second contact shoe for resetting the signal device.

2. In a train controlling mechanism the combination with a wheeled vehicle having a contact shoe, of an electro-magnet; a circuit normally including said shoe and magnet; a signal in the vehicle and normally maintained in the inoperated position by said electro-magnet and released upon the deenergization of said magnet; an air pipe having a valve; a second shoe operatively 0 engaging said valve to allow air under pressure to pass therein and means adjacent the

signal device and communicating with said air pipe to reset the signal.

3. In a train controlling mechanism the combination with a wheeled vehicle having an air-brake valve, of an electro-magnet on the vehicle to control the said valve; a contact shoe also on the vehicle; a circuit including the contact shoe and magnet; a signal device also on the vehicle; an electro-magnet for holding said signal in the safety position; a second contact shoe on the vehicle; a second circuit including said latter magnet and contact shoe and means actuated by the first-named contact shoe for resetting the signal device.

4. In a train controlling mechanism the combination with a wheeled vehicle having an air-brake valve, of an electro-magnet on the vehicle to control the said valve; an air 80 brake contact shoe also on the vehicle; a circuit including the brake contact shoe and magnet; a signal device also on the vehicle; an electro-magnet for holding said signal in the safety position; a signal contact shoe on the vehicle; a second circuit including said latter magnet and signal shoe; and pneumatically-operated means actuated by the air brake contact shoe to reset the signal device.

5. In a train controlling mechanism the combination with a wheeled vehicle having a contact shoe, of an electro-magnet; a circuit normally including said shoe and magnet; a signal on the vehicle which is normally maintained in the inoperated position by said electro-magnet and to be released upon the deenergization of said magnet; an air-brake valve also on the vehicle; a second contact shoe; an electro-magnet for controlling said air-brake valve; a circuit including the second contact shoe and the air-brake magnet; an air storage reservoir on the vehicle; a pipe from the reservoir and leading to the said signal,—said pipe having a valve therein to coat with the said second contact shoe to permit the passage of air when the shoe is operated; means operated by pressure from said pipe to reset the signal; another pipe from the air reservoir 105 and terminating adjacent to the air-brake valve and means operated by the air pressure in said latter pipe to reset the air brake valve.

In testimony whereof we affix our signatures in presence of two witnesses.
